(57) **CLAIM**

The ornamental design for a confetti dispensing device as shown and described.

DESCRIPTION

FIG. 1 is a front, top perspective view of a confetti dispensing device, showing my new design;

FIG. 2 is a top view of the confetti dispensing device;

FIG. 3 is a bottom view of the confetti dispensing device;

FIG. 4 is front view of the confetti dispensing device;

FIG. 5 is a rear view of the confetti dispensing device;

FIG. 6 is a left side view of the confetti dispensing device; and,

FIG. 7 is a right side view of the confetti dispensing device.

The broken lines depict portions of the confetti dispensing device that form no part of the claimed design.

1 Claim, 6 Drawing Sheets
